UNITED STATES PATENT OFFICE.

EFFINGER E. WHIPPLE, OF EATON RAPIDS, MICHIGAN.

TONGUELESS CULTIVATOR.

SPECIFICATION forming part of Letters Patent No. 312,050, dated February 10, 1885.

Application filed February 29, 1884. (No model.)

To all whom it may concern:

Be it known that I, EFFINGER E. WHIPPLE, of Eaton Rapids, in the State of Michigan, have invented certain new and useful 5 Improvements in Tongueless Cultivators; and I do hereby declare that the following is a full, clear, and exact description thereof, reference being had to the accompanying drawings, and to the letters of reference marked 10 thereon, which form a part of this specification.

This invention relates to that class of wheeled cultivators known as "tongueless" cultivators, or that class of cultivators having two drag-bars or beams for supporting the cultivator 15 shovels or teeth, a transverse frame connecting the forward ends of the said bars, and two short independent wheel-axles which are pivotally connected with the ends of the said 20 frame or arch, and to which the horses for drawing the machine are independently attached.

The object of this invention is to provide an improved construction in cultivators of the 25 class above mentioned; and it consists in the matters hereinafter described, and pointed out in the claims.

In the machine herein shown as illustrating my invention, the drag-bars, instead of being 30 attached to the frame, are attached to the wheel-axles, which are pivotally connected with the frame in the usual manner, and the said frame is so constructed that the said axles and the drag-bars attached thereto may be ad- 35 justed laterally, or placed farther apart, or nearer together, as desired, the wheels, when the drag-bars are so adjusted, being moved in and out with the latter. By this construction the machine may obviously be made much 40 lighter and more compact than machines heretofore constructed, in which the wheels being laterally immovable have necessarily been placed at a distance apart greater than the maximum space between the drag-bars, in 45 order to provide space for the requisite lateral adjustment of said drag-bars upon the frame inside of the wheels. In the machine herein shown, also, the draft-bars, by which the horses are attached to the machine, instead 50 of being rigidly secured to the wheel-axles, are pivotally-connected with the latter, and

the drag-bars are attached to the wheel-axles in such manner that they may be fixed rigidly thereto, so that the course of the wheels may be guided or controlled by the handles upon 55 the drag-bars, instead of following the movement of the draft-bars, as heretofore. By this construction the operator is enabled to control the movements of the wheels and the forward ends of the drag-bars to a certain extent, 60 independently of the movements of the horses, so that the cultivator may be guided in turning around at the ends of rows, and in other circumstances, each drag-bar and its wheel operating somewhat in the manner of a wheelbarrow. 65 As a preferable construction in the frame or arch connecting the separate wheel-axles, which is bent or curved upwardly in a well-known manner, so as to pass over the row of corn, upon either side of which the drag-bars 70 travel, the upper horizontal bar or cross-piece connecting the vertical side pieces of the said arch is made vertically adjustable with reference to the said side pieces, in order that it may be placed nearer to or farther from the 75 axles, as desired. The object of this construction is to enable the said cross-piece to be raised in operating in places where the corn is high, and to be moved downwardly nearer the axles where the corn is lower, so as to 80 lessen the length of the vertical arms or side pieces of the arch, and thereby render the frame more rigid and lessen the liability of injurious strains thereon. In the form of machine herein illustrated as embodying my in- 85 vention, the wheel-axles are preferably attached rigidly at their inner ends to vertical rods or bars which form the vertical side pieces of the arch, and which are pivotally connected near their upper ends with a sepa- 90 rate horizontal bar forming the cross-piece of the arch. The connections between the vertical bars and the horizontal cross-piece are also preferably so constructed that the horizontal bar may be adjusted vertically upon 95 the vertical rods, and the latter adjusted longitudinally of the horizontal bar, the object of the adjustment first mentioned being to enable the height of the longitudinal bar above the ground to be changed for the purpose above 100 stated, and that of the second adjustment to permit the lateral adjustment of the drag-

bars, which are attached to the wheel-axles, with reference to each other. In this form of the machine the draft-bars and the drag-bars are preferably connected at adjacent points 5 with the wheel-axles, so that the draft is transmitted practically in a straight line to the drag-bars, and the pivotal axis of the connection between the wheel-axle and the transverse bar of the frame is also preferably vertically in line with the points of connection of the drag-bars and draft-bars, so that the action of the latter upon the wheel-axles has no tendency to rotate said wheel-axles or to throw the wheels out of line.

15 Other improved features of construction are embodied in the machine herein illustrated, which will be hereinafter fully described, and pointed out in the claims.

In the accompanying drawings, Figure 1 is 20 a perspective view of a tongueless cultivator embodying my invention. Fig. 2 is a side elevation of the same with the wheel nearest the eye removed. Fig. 3 is an enlarged detail section taken upon line $x-x$ of Fig. 2. Fig. 25 4 is an enlarged detail plan view of the connections between one of the wheel-axles and the cultivator-beam and draft-bar attached thereto. Fig. 5 is a perspective view of the parts shown in Fig. 4. Fig. 6 is a detail perspective view of a device for supporting the 30 drag-bars from the ground at times when they are not in operation.

In the form of machine embodying my invention illustrated in the accompanying drawings, A A are short wheel-axles, rigidly attached at their inner ends to the lower ends of the vertical rods B, which are pivotally connected near their upper ends to a transverse bar, C, which, together with the rods B, forms 40 the main frame or arch of the machine.

D D are the beams or drag-bars of the cultivator, said bars being connected at their forward ends with the wheel-axles A, and provided with handles D', and also with suitable 45 teeth or shovels, constructed in any usual or desired manner. As herein shown, beams D', provided with flexible and oppositely curved and twisted teeth d, are connected with the drag-bars D by means of springs d', this construction in the teeth and means for attaching them to the bars being substantially similar to that set forth in a separate patent, heretofore granted to me.

E E are separate draft-bars, which are connected with the axles A, near the rods B, preferably by means of pivot-bolts e, inserted through apertures in the bars and axles, and provided at their forward ends with hooks e', with which suitable single-trees may be connected for the attachment of horses.

In the form of device herein shown the front ends of the drag-bars D are connected with axles A by means of vertically-apertured coupling blocks or sleeves F, placed upon the rods 65 B above their points of attachment to the axles A, and to which the forward ends of the draft-

bars are connected by means of plates D', attached to the bars, and secured by means of horizontal pivot-pins f' in slots f in the blocks F, the object of this construction being to permit the requisite vertical play in the drag-bars and to allow the teeth to be lifted out of the ground in transporting the machine from place to place and in turning around. The sleeves F may be clamped in any desired manner to the rods B, so as to hold the drag-bars rigid with reference to the axles, for the purpose of enabling the movements of the wheels to be controlled by the bars, the device for this purpose (shown in the accompanying drawings) consisting of 80 bolts F', tapped through the sleeve F, and constructed to abut against the said rods. When the joints between the drag-bars and the axles are so constructed that the said bars may be either loosely or rigidly connected therewith, 85 as above described, means are preferably provided for rigidly connecting the draft-bars E to the said axles, whereby the wheels may be controlled as desired either by the draft-bars, as has been usual heretofore, or by the drag-bars in the manner above set forth, the device for this purpose herein shown consisting of apertures a, located in rectangular portions A' of the axles in advance of the pivot-pins e, through which apertures and corresponding 90 apertures in the draft-bars suitable pins, as indicated at a', Fig. 5, may be inserted for holding said bars immovably in place. The axles A and rods B may consist of separate pieces secured together, or, as shown in Fig. 100 3, they may be formed of a single metal rod bent at right angles. The part A' may be formed integral with the rod comprising the axle and rod B, or it may consist, as shown, of a separate cast piece attached to said rod. 105

As a simple and economical construction in the pivotal connection between the rods B and the transverse bar C, the upper portions of said rods are inserted in sleeves G, which are attached to the cross-bar C, and rest upon collars G, secured to the said bars.

For the purpose of enabling the distance above the ground of the cross-bar C to be changed according to the height of the corn to be operated upon, the said bar C is made 115 vertically adjustable with reference to the rods B, this adjustment preferably being accomplished by making the collars G' vertically movable upon the rods B. When the last-mentioned construction is used, the collars 120 may be held upon the rods by any suitable clamping device, that herein shown consisting of a set-screw, g, inserted through the collar and bearing at its inner end against the rod.

An important advantage of making the bar 125 C vertically adjustable is, that when the machine is used in cultivating corn which is relatively short, the bar may be lowered so as to bring the wheel-axles nearer the said bar, and to thereby lessen the strains upon the bar and 130 connections occasioned by the increased leverage of the rods B when they are long. As

corn usually grows to a greater height in soft and rich soil than in that which is otherwise, it is usually found in practice that the bar may be placed nearer the wheel-axles, so as to give the greatest rigidity to the frame at times when the machine is operating in hard and stony ground, upon which the corn is relatively low, and in which the machine is liable to the most severe strains.

In order to provide means in the machine constructed as above set forth for adjusting the distance between the drag-bars, a sliding connection is formed between the rods B, to which the said bars are attached, and the transverse bar C, joining the rods, so that said rods may be moved longitudinally of the bar and firmly secured in their changed position.

As a preferable construction in the parts above referred to, the sleeves G, in which the rods B are constructed to rotate, as before described, are provided with projecting portions or short sleeves G^2 , provided with horizontal apertures g' , arranged to pass at one side of the vertical apertures of the sleeves, and in which the bar C is constructed to fit and slide.

Any well known or suitable means may be used for clamping the sleeves G^2 to the bar C, the device herein shown for this purpose consisting of an ordinary set-screw, g^2 . The bar C may be of circular or other form in cross-section, but, as herein shown, said bar is rectangular and the apertures in the sleeves G^2 are of corresponding shape, so as to prevent the rotation of the sleeves upon the bar and to retain the rods B relatively parallel. The same effect may obviously be produced by using a round bar with a spline or groove constructed to engage a corresponding groove or projection in the sleeves; but these and similar devices obviously being equivalents of the square bar shown, the invention as it relates to the parts mentioned is not limited to any particular means for preventing the rotation of the sleeves upon the bar C.

In order to enable the rods B to be rigidly secured in the sleeves G, if desired, set-screws g^3 are herein shown as inserted in said sleeves in position to bear upon the rods.

Means have heretofore been used in cultivators for supporting the drag-bars when it is desired to remove the teeth thereon from the ground in moving the machine from place to place or turning it around, consisting of devices constructed to support the said bars from an elevated part of the machine-frame, and in tongueless cultivators rearwardly and downwardly extending arms rigidly connected with the lower part of frame, with their rear ends in position to rest upon the ground considerably behind the wheel-axles, have been used in connection with such supporting devices in order to prevent the frame from tipping backward when the bars are upheld in the manner described.

As an improved construction in means for elevating and supporting the drag-bars, de-

vices are herein shown for the purpose mentioned, which are constructed as follows: Pivoted upon each of the drag-bars D, at some distance to the rear of the point of their connection with the machine-frame, and preferably somewhat in advance of the cultivator-teeth, are bars or arms H, of which two are

preferably used on each bar, the said arms being secured by pivot-pins h at their ends to the said beams, so that they may be placed in a downwardly and rearwardly inclined position, with their lower ends resting upon the ground, as shown in Fig. 6 and in dotted lines in Fig. 2, or folded horizontally into the position shown in Figs. 1 and 2. The arms H are made of such length that when thrown downwardly with their lower ends resting upon the ground they will sustain the drag-bars in an upwardly-inclined position, and with the teeth thereon clear of the ground, and the lower ends of said bars are preferably provided with rearwardly-bent portions or feet h^4 , constructed to rest upon the ground so as to slide readily over it in the advance movement of the machine when the teeth are lifted.

Any suitable means may be provided for limiting the rearward movement of the arms H, so that when thrown downwardly they will stand at a rearward inclination, with the part h^4 resting upon the ground, the means for the purpose herein shown consisting of pins h^5 inserted in the beams below and slightly to the rear of the pivotal points of the arms. The free ends of the arms may be upheld when they are not in use by means of a suitable hook or other supporting device upon the beams or arms. A preferred means of supporting the said arms is herein shown, however, which consists of a weight, H', applied to an upwardly-extended portion, h^2 , of the arm H, the said weight being sufficiently heavy to overbalance the lower portion of the arm, and thereby retain it in its horizontal position. In case two arms, H, are used, as illustrated in Fig. 6, the said arms are placed one upon each side of the beam, and are spread apart at their lower ends so as to bring the feet h^4 at some distance apart laterally, in order to prevent any lateral or tipping motion of the beam, the lower portion of the arms, when the last construction is used, preferably being connected by a brace, h^3 . The arms H, when not in use, remain in a horizontal position, with their lower ends near the front ends of the beams D, as indicated in Fig. 1, and when during the operation of the machine it is desired to lift the cultivator-teeth from the ground said arms are swung downwardly until their ends strike and engage the surface of the ground, when the continued forward motion of the machine will cause the bars to be lifted and the arms to take a rearwardly-inclined position, as indicated in Fig. 6. When it is desired to lower the drag-bars so as to bring the teeth again into operation, said drag-bars are lifted by means of the han-

dles D' until the lower ends of the arms H are free from the ground, when the said arms may be swung upwardly and forwardly by the hand, and will be held in their horizontal position 5 by the action of the weight H'.

In order to enable the arms to be moved when desired by the operator without leaving his position behind the cultivator, suitable operative connections between the said bars and 10 the handles of the cultivator are desirably provided, which, as herein shown, consist of rods I, pivotally connected with the upwardly-projecting portion h² of the arms H at a point above the pivotal point of said arms and extending rearwardly to the rear ends of the handles D'. The said rods I, as herein shown, are provided with upturned ends i, adjacent to the curved ends of the handles D', and located in such position that when it is desired 15 to throw the arms H downwardly the hands of the operator, which grasp the curved parts of the said handles D', may be slipped along said curved parts until they encounter the upturned ends i, and thereby throw the part h² 20 of the arms H forwardly and the lower ends of the said arms downwardly. The portion h² of the arm H is, as herein shown, bent or deflected upwardly or forwardly from the pivotal pin of the said arm to the point of connection with the rod I, so that when the said arm is in a horizontal position, as indicated 25 in Fig. 1, the rod will operate upon the part h² in proper direction to swing the said arm about its pivotal point.

35 The means for supporting the drag-bars herein shown are obviously applicable to tongued and other kinds of cultivators, as well as to the cultivator herein shown, and I desire, therefore, to claim such supporting device, 40 broadly, without limitation as to the particular form of cultivator to which it is applied.

In order to support the frame or arch herein shown in an upright position when the drag-bars D are supported by the arms H, as 45 above described, the pivotal connections between the sleeves or couplings F and the bars D are preferably constructed to permit a limited vertical movement only in the bars. In the construction herein shown for this purpose, and illustrated more clearly in Fig. 5, the plates D³, which are secured to the forward ends of the bars D, as before described, are provided with upturned ends d³, which fit in the slots f in the said couplings F, the parts 50 d³ being constructed to abut at their lower portions, d⁴, against the inner surfaces, f², of the slots f when the bars are horizontal, and the upper portions, d⁵, of the forward edges of the said parts d³ being slightly inclined to the parts 55 d⁴, so as to strike the said inner portions, f², when the bars D are swung slightly upward from their horizontal positions.

The connections of the drag-bars D and the couplings F are arranged to permit a sufficient 60 movement in the said bars to allow one bar to be swung upwardly without moving the

frame when the bars are lifted independently, as may be the case when the arms H are thrown down at different times or when the arms are released by lifting the drag-bars 70 separately.

I claim as my invention—

1. The combination, with the frame or arch of a tongueless cultivator, of separate wheel-axes pivotally connected with the frame, 75 drag-bars attached to the wheel-axes by laterally-rigid connections, and draft-rods pivotally connected with said wheel-axes, substantially as and for the purpose set forth.

2. The combination, with the frame of a 80 tongueless cultivator, of separate wheel-axes connected with the frame, drag-bars and draft-bars connected with the wheel-axes, and pivotal connections between the drag-bars and the axles and the draft-bars, and the axles 85 constructed to permit either the drag-bars or the draft-bars to be rigidly secured to said axles as desired, substantially as and for the purpose set forth.

3. The combination, with the separate 90 wheel-axes A, drag-bars attached to the axles, and vertical rods B, rigidly secured to the said axles, of a transverse bar, C, connecting the rods B, sleeves G, constructed to rotate upon the rods B, and having sliding connection with the bar G, and means for clamping the said sleeves to the said bar, substantially 95 as and for the purpose set forth.

4. The combination, with the wheel-axes A, drag-bars connected with the axles, and 100 vertical cylindrical rods B, rigidly connected with the said axles, of a transverse bar, C, connecting the said rods B, sleeves G, constructed to rotate upon the rods B, and rigidly connected with the transverse bar C, collars 105 G', located upon the rods B, beneath the sleeves G, and means for adjustably securing said collars to the rods, substantially as and for the purpose set forth.

5. The combination, with the separate 110 wheel-axes A, vertical rods B, rigidly attached to said axles, and drag-bars D, of coupling-blocks F, attached to the drag-bars, and provided with cylindric apertures constructed to fit upon the cylindric lower ends of the rods 115 B, clamping devices for securing the coupling-blocks rigidly upon the said rods, draft-bars connected with the wheel-axes at points adjacent to the rods, and a transverse bar, C, pivotally connected with the said rods, substantially 120 as and for the purpose set forth.

6. The combination, with the drag-bar of a cultivator, of an arm, H, pivotally connected with the said bar, and a counterbalance-weight, H', applied to the said arm above its pivotal point, substantially as and for the purpose set forth.

7. The combination, with the drag-bar of a cultivator, of an arm, H, pivotally connected with the said bar, a counterbalance-weight, 130 H', attached to the arm above its pivotal point, and a rod, I, connected with said arm

and extending to a point upon the machine within the reach of the operator, substantially as and for the purpose set forth.

8. The combination, with the drag-bar of a 5 cultivator having a handle, D', of an arm, H, pivotally connected with the said drag-bar, and a rod, I, connected with the said arm at one end, having sliding connection with the handle D' at its opposite end, and provided with an ap- 10 pertured portion, i, substantially as and for the purpose set forth.

9. The combination, with the frame and drag-bars of a tongueless cultivator, of coup- 15 ling-blocks F, connected with the frame, and

vertical plates D³, attached to the bars and 15 pivotally connected with the said blocks, the plates B³, and the coupling-blocks being pro- vided with abutting surfaces f², d⁴, and d⁵, constructed to limit the vertical play of the drag-bars, substantially as and for the purpose 20 set forth.

In testimony that I claim the foregoing as my invention I affix my signature in presence of two witnesses.

EFFINGER E. WHIPPLE.
